UNITED STATES PATENT OFFICE.

THOMAS J. AKERS, OF LATAH, WASHINGTON.

RAILWAY-SPIKE.

No. 909,509.

Specification of Letters Patent.

Patented Jan. 12, 1909.

Application filed July 16, 1908. Serial No. 443,832.

To all whom it may concern:

Be it known that I, THOMAS J. AKERS, a citizen of the United States, residing at Latah, in the county of Spokane, State of

5 Washington, have invented certain new and useful Improvements in Railway-Spikes; and I do hereby declare the following to be a full, clear, and exact description of the invention, such as will enable others skilled in 10 the art to which it appertains to make and use the same.

This invention relates to railway spikes, and has for one of its objects to provide a divided spike of improved construction 15 which cannot be withdrawn from the tie except by the application of an abnormal strain, and which will not work loose under normal conditions.

Another object of the invention is to provide 20 a divided spike of unequal portions so constructed that the larger portion will assume a position at right angles to the longitudinal plane of the tie, while the smaller portion is separated and directed obliquely 25 into the tie in the opposite direction.

With these and other objects in view, the invention consists in a spike having a laterally directed head at one end and wedge shaped at the other end, the face of the 30 wedge next to the extended head being relatively short and the other side relatively long and with a lateral recess in the side of the spike opposite to the head and a tongue extending normally into the recess, the inner 35 face of the tongue at its free end inclined to the longitudinal plane of the spike whereby a cavity is formed between the tongue and the body of the spike.

The invention further consists in certain 40 novel features of construction as hereafter shown and described and then specifically pointed out in the claims, and in the drawings illustrating the preferred embodiment of the invention, Figure 1 is a sectional view 45 tail of a railway rail and a portion of a tie with the improved spike shown in operative position in connection therewith. Fig. 2 is a side elevation of the improved spike. Fig. 3 is a rear elevation.

50 The improved device comprises a spike formed with a stock or shank 10 having a head 11 at one end and an unequal wedge shaped point 12 at the other end, one side 13 of the point being relatively long and 55 the other side 14 being relatively short, as shown. For the purpose of this description

the side of the spike from which the head 11 extends is referred to as the front, and the side in which the tongue is formed as the rear.

60 Formed in the rear of the stock 10 intermediate the ends is a recess 15 into which a tongue 16 is directed, the recess terminating in a shoulder 17 at right angles to the shank and with the inner face of the tongue at its 65 terminal inclined at 18 and with a recess at 19 whereby a shoulder 20 is formed. The terminal of the tongue is thus "barbed" while an angular open cavity 21 is formed between the body of the stock and the 70 barbed point of the tongue.

When a spike thus constructed is driven 75 into the tie, represented at 22, the longer face 13 of its wedged end would naturally cause the spike to pursue a course toward the rail represented at 23, but when the cavity 21 passes into the body of the tie the fibers of the wood enter the cavity from the ends and bear against the inclined face of the tongue 16 and force the latter outwardly, and 80 as soon as the point of the tongue engages the tie, it is separated and forms a course for itself curving away from the body of the spike, as shown, and creates a strong lateral strain upon the spike while the tendency of 85 the latter is to be drawn into the tie beneath the rail. The influence of the long wedge face 13 and the tongue 16 are thus placed to cause the separation of the two parts of the spike as shown in Fig. 1, with the separated 90 parts in position obliquely to the longitudinal plane of the tie. The elasticity of the fibers of the wood cause them to enter the cavity 21 and also to bear against the shoulder 20 of the barbed end of the tongue and thus 95 firmly "lock" the spike into the tie, and prevent its withdrawal unless abnormal strains are applied. The spike will thus retain its position against any strains to which it will be subjected, under normal conditions.

100 The spike can be inexpensively manufactured, as the cost of manufacture will not be greater materially than that for manufacturing an ordinary spike while the advantages 105 of its use are materially greater as will be obvious.

What is claimed is:

1. A spike comprising a stock having a laterally extending head at one end and with the opposite end wedge shaped, with the face 110 next the extended head relatively short and the other side relatively long, a lateral recess

in the side of the spike opposite to the extended head, and a tongue directed normally into said recess with the inner face thereof at the free end inclined to the longitudinal 5 plane of the spike.

2. A spike comprising a stock having a laterally extending head at one end and with the opposite end wedge shaped, with the face next the extended head relatively short and 10 the other side relatively long, a lateral recess in the side of the spike opposite to the ex-

tended head, and a tongue directed normally into said recess with the inner face thereof at the free end barbed, to form an angular cavity between the tongue and the body of 15 the spike.

In testimony whereof, I affix my signature, in presence of two witnesses.

THOMAS J. AKERS.
